(57) **CLAIM**

The ornamental design for a display screen or portion thereof with a graphical user interface, as shown and described.

DESCRIPTION

The sole FIGURE is a front view of a display screen or portion thereof with a graphical user interface showing our new design.

The broken lines, including those showing a display screen or portion thereof and those depicting portions of a graphical user interface, form no part of the claimed design. The ornamental design for a display screen or portion thereof with a graphical user interface, shown in the FIGURE may be within a graphical user interface, such as a radio network topology graphical user interface, of a computer.

Shading represents areas of contrasting appearance and forms part of the claimed design.
